5 SHEETS—SHEET 1

The drawing illustrates a complex mechanical assembly, likely a film projector. It features a large wheel at the bottom left, labeled 20, which is connected to a series of gears and shafts. A prominent vertical cylinder, labeled 12, is positioned on the right side. Various mechanical parts are labeled with numbers such as 3, 5, 15, 16, 52, 53, 160, 161, 162, 20, 22, 24, 45, 88, 111, 87, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 6610, 6611, 6612, 6613, 6614, 6615, 6616, 6617, 6618, 6619, 6620, 6621, 6622, 6623, UNITED STATES PATENT OFFICE.

RIMMON C. FAY, OF PHILADELPHIA, PENNSYLVANIA, ASSIGNOR TO FAY MACHINE TOOL COMPANY, A CORPORATION OF PENNSYLVANIA.

LATHE.

No. 910,466.

Specification of Letters Patent.

Patented Jan. 19, 1909.

Application filed February 9, 1906. Serial No. 300,229.

To all whom it may concern:

Be it known that I, RIMMON C. FAY, a citizen of the United States, residing at Philadelphia, in the county of Philadelphia and State of Pennsylvania, have invented certain new and useful Improvements in Lathes, of which the following is a specification.

The invention to be hereinafter described relates to machine tools and more particularly to that type known as lathes, wherein the work or blanks to be treated are preferably rotated, while the cutting instrumentalities are held and fed to their cutting position by suitable tool holders.

The general objects of the present invention are to provide a machine of the above character which will embody a simplified form of mechanism for simultaneously performing a multiplicity of operations on the same blank, wherein the speed of the parts may be either manually or automatically controlled, and the machine be automatically or manually stopped when the article being treated is finished, thus after the machine has been adjusted to the performance of certain work, no further attention is required of the operative than the proper supply of blanks.

With these generally stated objects in view, the invention consists of the parts and combinations as hereinafter described, and definitely pointed out in the claims.

In the embodiment of the invention herein selected for illustration the machine is provided with a series of cutting instrumentalities for simultaneously acting upon the article to be treated, the carriers for such cutting instrumentalities being operated or fed by cam devices which derive their motion from the driving shaft through a suitable train of gearing. The general form and character of the said cam devices is such that one rotation thereof is sufficient to carry the cutting tools simultaneously through a complete cycle of their cutting operation, whereupon the parts may be automatically returned to their starting position for a fresh cut, all as will be described.

In the drawings:—Figure 1 is a side elevation of a lathe embodying one form of the present invention. Fig. 2 is a side elevation similar to that of Fig. 1 taken from the opposite side of the machine. Fig. 3 is a longitu-

dinal central section of the machine, some of the parts being broken away and others shown in elevation to better illustrate the mechanical disposition of parts. Fig. 4 is a transverse section on the line $x-x$, Fig. 2. Fig. 5 is a like transverse section on line $y-y$, Fig. 2, some of the parts being broken away. Fig. 6 is an end view or elevation of the machine, looking in the direction of the arrow, Fig. 1, some of the parts being broken away to show devices beyond. Fig. 7 is a detail view of a modified form of means for giving the face or front tool holder a transverse tilting movement; Fig. 8 is a detail of the end tool holder to be described; and Fig. 9 is a plan view of a lathe embodying the invention.

The lathe-bed, 1, may be of any usual or desired form, preferably supported upon legs or standards 2, and mounted thereon in suitable manner is the head stock 3 and tail stock 4, the former of which carries the lathe spindle 5. Disposed transversely of the head stock 3 is the driving shaft 6 provided with a pulley 7 which, by means of belt 8, may be driven from any suitable source of power. The driving shaft 6 is provided with a worm 9, which meshes into an annular worm wheel 10 detachably secured to a flange 10' on the lathe spindle, see Fig. 3, said worm and worm wheel being preferably interchangeable with other forms of such parts to allow latitude in speed reduction between the driving shaft and lathe spindle, as will be readily understood by one skilled in the art.

Mounted in suitable bearings 11 and substantially central of the lathe-bed is the main or front feed spindle 12 which is capable of endwise movement by means to be described. Loosely disposed upon the front feed spindle 12 is the sleeve 13, which is contained in suitable bearings 14 of the lathe-bed, said sleeve having secured thereto the worm-wheel 15 to which is connected the cam cylinder 16. The connection between the cam cylinder 16 and worm-wheel 15 may be of any usual or desired character, but herein it is shown as a left hand screw thread connection 17, as a convenient form, because, since the direction of rotation of the worm-wheel is always the same, this character of connection will serve to tightly join the parts and yet permit their ready separation when desired. Secured to the cam drum cylinder 16 is the outwardly extended skeleton frame

160 having a bearing 161 which serves as a mutual support for the cam cylinder and front feed-spindle 12, and is of importance in operating on long work.

5 Disposed transversely of the lathe-bed in suitable bearings is the shaft 18 provided with a worm 19 in driving connection with the worm-wheel 15, as best shown in Figs. 3 and 6. Loosely mounted on the shaft 18 is 10 the pulley 20 driven from a small pulley 21 on the driving shaft 6 by means of a belt 22, or other suitable power transmitting means, and secured to pulley 20, see Fig. 6, is a small gear 23, thus the pulley 20 and gear 23 15 rotate independently of the shaft 18. In order, however, to drive the shaft 18 and its worm 19 from the pulley 20 and gear 23 a train of reducing gearing is provided, as best indicated in Figs. 1, 2 and 6.

20 Meshing with the small gear 23, Fig. 6, is the gear 24, Fig. 1, fixed to a shaft 25 extending transversely of the lathe-bed, and upon the opposite end of this shaft 25 is a small gear 26, Fig. 2, forming one of a system 25 of change gears whereby variable speeds may be obtained. The small gear 26 meshes with gear 27, the hub of which carries gear 28. This latter gear meshes with gear 29, the hub of which is also provided with a gear 30. 30 Said gear 30 meshes with the pinion 30', which also meshes with an intermediate gear 31, which in turn meshes with gear 32 mounted loosely upon shaft 18. Keyed to shaft 18 is a disk 33 (Fig. 6) provided with a plurality 35 of cam-shaped slots in which are located rollers, the same constituting a clutch illustrated in dotted lines, (Fig. 2). By means of this arrangement, shaft 18 and its worm 19 are given operative movement under normal 40 working conditions.

From the construction thus far described, it will be seen that the worm 19 and the intermeshing worm wheel 15 and connected cam drum or cylinder 16, are driven from the 45 driving shaft through a system of reducing gearing, whereby the cam-drum is slowly rotated for a purpose that will hereinafter appear. While a particular system of reducing gearing and change gears have been 50 described as one embodiment of this feature of the lathe structure, it is to be understood, of course, that the invention itself is not circumscribed by these details.

The interior surface of the cam drum 16 is 55 adapted to receive and have secured thereto in a detachable manner, as by the pins or screw bolts 34, cam plates 35, between which may be formed a cam groove 36 of a shape or form to suit the character of the work to be 60 done by the facing tools, as will presently appear. Secured to the main or front feed spindle 12 is an arm or dog 37 having a roller 38 which travels in the cam groove 36 as the cam drum revolves, whereby the said feed spindle is gradually moved longitudinally.

Secured to the feed spindle 12 so as to move longitudinally therewith is the front feed carriage 39, Figs. 3 and 4, to which is secured the tool holder 40, said carriage extending to the front of the lathe-bed and 70 there being provided with a wedge-shaped resting edge 41, Fig. 1. This resting edge is preferably mounted loosely so as to slide at one end on a pin or rod 42 secured in the ears 43 of the carriage, that end of the pin or rod 75 nearer the head stock being higher than the other end, as indicated in Fig. 1. When the cutting tool is in operative position with relation to the work, it and the resting edge 41, are substantially the same distance from the 80 center of the feed spindle 12, so that when the carriage 39 is tilted by means of the former plate 44, to be described, the spindle 12 is oscillated and like inward and outward movements will be given the cutting tool and 85 resting edge about the center of said feed spindle.

Mounted in bearings 45, 45, secured to the lathe-bed is the former carrier 46 to which is secured the former plate 44, preferably by means of countersunk screws 47, said plate having at each end abrupt recesses 48, 48, into which the resting edge 41 drops at each travel of the carriage 39, as will presently appear. The contour of the former 90 plate 44 is made to suit the character of work to be done by the front cutting tool and its surface receives the full thrust of said tool during its cutting operation. For example, if the work requires the turning off of the 95 crown face of a pulley, where the crown belies outward, the former plate 44 is shaped with downward converging side portions as illustrated in Fig. 1, thus allowing the resting edge 41 to gradually drop the cutting edges 100 of the tools as the carriage moves along the surface to be cut. In this way any curved or oblique surface or surfaces may be formed by a complementary form given to the surface of the former plate. In this operation 105 of the device, that is, in cutting a surface that requires the carriage to move along the surface to be cut, the former carrier 46 is held stationary by means of the bolts 49 which pass through slots 50 in the bearing 45 to the 110 right in Fig. 1. In the action of the device, as thus described, the front spindle 12 is moved by the cams of the cam drum and the carriage 39 is correspondingly moved. At the beginning of the operation the resting 115 edge 41 stands upon the cut away portion 48 of the former plate 44, and as the carriage is fed longitudinally of the machine towards the work, the edge 41 reaches the abrupt rise at the edge of the cut-away portion 48, and before mounting it, allows the carriage to 120 continue its movement alone until the edge 41 has reached the ear 43 near the right hand end of the pin 42, whereupon the edge 41 is forced over the rise onto the forming surface 125 130

of the former plate. In this sliding movement to the end of the pin 42 the edge 41 acting as a wedge raises the carriage a certain amount due to the inclination of pin 42, thus bringing the cutting tools into line for cutting. When the end of the operation is reached the resting edge 41 drops into the cut away portion 48 at the left of the former plate, and on the return motion a sliding action takes place between the resting edge 41 and the pin 42 in the reverse direction from that described, thus lowering the cutting tools from the work, by reason of the inclination of the pin 42, as will be readily understood. It will be observed that the spindle 12 oscillates with the tool holder 39 by reason of the latter being secured to the former, as heretofore described.

Should a transverse movement of the front cutting tools be required without a corresponding longitudinal movement as just described, the former carrier 46 may be provided with an arm or dog, which will be passed through a slot 51 near the left of the former carrier, and said arm or dog made to engage a cam slot or groove 52 formed by cam pieces 53, 53, secured to the exterior of the cam-drum. At the same time, the bolts 49 will be loosened or removed and the end- wise movement of the front spindle 12 be arrested either by loosening the arm 37, Fig. 3, or providing a circular portion to the cam groove 36. In thus making a direct transverse cut by means of the front cutting tools, any desired form of former plate may be employed, as will be obvious, but in practice, it is found desirable in many cases to provide a simple wedge form of plate, such as shown in Fig. 7, wherein the former plate 54 is secured to the now slidable former carrier 46, by means of suitable devices, such as screws 55 or the like. Obviously, of course, other variations in the parts and their adjusted relation may be made without departing from the spirit of the invention, one embodiment of which is furnished in the drawings and descriptions herewith.

Disposed in substantially parallel relation with the front feed spindle 12 is the back shaft or spindle 56 supported in suitable bearings 57, 57, in the lathe-bed, said shaft or spindle being free to be moved longitudinally and oscillated in said bearings and provided with tool holders 58, 58, appropriately secured thereto. Projecting from the back shaft or spindle 56 near one end thereof is an arm or dog 59 carrying a roller 60 adapted to travel in the groove 61 formed by cam pieces 62, 62, detachably secured to the outer surface of the cam drum 16, Fig. 2, whereby under conditions to be described, longitudinal movement may be given the back shaft or spindle in a manner similar to that described for the front feed spindle. Obviously, the cam pieces 62—62 may be acted on

to give such motions to the back shaft or spindle that the respective tools carried thereby will perform independently of each other precisely the work required to be done.

Secured to the lathe-bed below the back shaft or spindle 56 is a bracket 63 carrying a horizontal cam plate 64, preferably circular in shape and provided on its upper surface with a groove 65 which may be straight or curved in form, but is preferably arranged diametrically of the cam plate 64. The bracket 63 is preferably formed of two similar parts, as shown in Fig. 2, held together by a clamping bolt 66 whereby, upon loosening of the bolt 66, the cam plate 64 may be rotated and give a suitable position to the work to be performed as will presently appear. Secured to the back shaft or spindle 56 and depending therefrom is the controlling arm 67, said arm being preferably connected to the back shaft or spindle 56 by means of a clamping bolt 68, and its lower end being in engagement with the groove 65 in the cam plate 64. The lower end of the controlling arm 67 may preferably be provided with a roller 69 in order to overcome any friction between the parts.

From the construction thus far described with respect to the back shaft or spindle and its operating means, it will be apparent that if the cam plate 64 be so set that its groove 65 is parallel with the back shaft or spindle, no rocking movement will be imparted to the back shaft or spindle as it is moved longitudinally by means of the groove 61 formed upon the cam drum; but if, on the other hand, it is set at an angle to said back shaft or spindle not greater than 45°, then, as the back shaft or spindle is moved longitudinally by virtue of the cam groove 61, the controlling arm 67 will travel in the groove 65 to cause the back shaft or spindle to move about its axis, thus imparting to the cutting tools carried by the holders 58 not only a movement longitudinally of the lathe-bed, but also a movement transversely thereof. Should the required cutting angle of the tools upon the edge of the work be 45° or more with relation to the back spindle, the rotary motion of the shaft 56 will predominate over the longitudinal motion, and if longitudinal motion were thus attempted to be given to the back spindle 56 through the arm 59 and cam groove, there might be a binding action between the end of the controlling arm and the groove of the cam plate, to overcome which objection the following mechanism is provided. Secured to the sleeve 13, Fig. 3, on the worm wheel 15 is a cam 70 loosely mounted upon the front spindle 12, Figs. 2, 3 and 5, and detachably secured to the back spindle 56 is a cam arm 71 which is adapted to bear upon the cam 70 and passes through an opening 72, Fig. 2, in the lathe-bed for this purpose. To maintain

the cam arm 71 in operative relation to the cam 70 a weight 73 is employed, Figs. 2 and 4, which is connected to the controlling arm 67 by means of a flexible chain or cord 74 and passes over a loose pulley 75. When the construction thus described is being employed the arm 59 on the back spindle 56 is removed or loosened so that it has no effect upon the longitudinal movement of the said spindle. When the periphery of the cam 70 departs from the circle, a movement is imparted to the cam arm 71 to rotate the back spindle 56 about its axis and to move thereby the controlling arm 67, the end of which is in the groove 65 of the cam plate 64, which is now adjusted to an angle of 45° or more with respect to the back spindle. From the construction thus far described, it will be apparent that as the cam arm 71 thus rocks the back spindle 56 the controlling arm 67 will cause a longitudinal movement of said back spindle depending upon the angular arrangement of the slot 65 with respect to the axis of the said spindle. If the tools carried by the holders 58 are to be moved directly transversely of the lathe-bed the groove 65 in the cam plate 64 would be adjusted at right angles to the axis of the back spindle 56, under which condition no longitudinal movement of the back spindle would take place.

Obviously, when the back spindle 56 is given its longitudinal movement by means of the arm or dog 59 and the cam groove 61 on the surface of the cam-drum 16, its rotative movement is imparted by means of the cam plate 64 and controlling arm 67, and in this case the cam arm 71 is loosened upon the back spindle 56 and held out of engagement with the cam 70. On the other hand, when the rotative movement of the back spindle is imparted by means of the cam arm 71 and cam 70, its longitudinal movement is secured by means of the cam plate 64 and controlling arm 67, in which event, the arm or dog 59 is turned out of engagement with the cam groove 61. It is obvious, also, that many changes might be made in the details of the parts thus described with respect to the motions of the back spindle 56 without in any way departing from the scope of the invention.

By means of the construction hereinbefore described it is possible to perform simultaneously a number of operations upon the same blank with the tools controlled by the back spindle 56 and those controlled by the main or front spindle 12. For instance, the front tools may be giving roughing and finishing cuts over the crown surface of the belt pulley and at the same time the tools of the back spindle can be truing up and rounding off the edges, finishing the belt pulley in the time that an ordinary lathe would take to do either operation that happened to be the longer. The cycle of cutting operations thus

simultaneously performed by the front and back spindles and their connected tools is controlled from the same cam-drum, upon the interior and exterior surfaces of which cam pieces may be secured in conformity with the character of work to be done, and such cycle of operations are completed and the tools returned to the starting point during a single rotation of the cam-drum. Thus it is that the cam-drum is to be driven from the main driving shaft by a system of speed reducing gearing of the general character described. It is desirable, however, that upon the completion of the cycle of cutting operations, or it may be at other times, that the speed of the cam-drum be increased either to return the parts to the beginning of a cutting cycle or for other purposes, for which reasons the following means may be employed as one type of such speed changing devices. Keyed to the end of shaft 18 is one member 76 of a clutch which is adapted to be moved into engagement with a complementary member 77 secured to the face of the pulley 20, which is loose on the shaft 18, a yoke 78 being provided to slide the clutch member 76 into and out of engagement with the member 77. Obviously when the clutch members are engaged, the shaft 18 and its worm 19 will be rotated at the relatively high speed of pulley 20, the ratchet 33 connecting the reducing gear 32 to said shaft 18, permitting such movement. This change of speed may be done at any time by hand by means of a lever 79 on a shaft 80, to which the yoke 78 is secured.

Extending transversely of the lathe-bed is the pattern shaft 81 provided with a beveled gear 82, meshing with a corresponding gear 83, Fig. 5, on the counter shaft 84 extending longitudinally of the lathe-bed, said counter-shaft deriving motion from the worm 15 through the sleeve 13 and pinion 85 and the like pinion 86 secured to the counter-shaft, Fig. 3. Secured to the end of the pattern shaft 81, Figs. 1 and 5, is a disk 87 to which a series of pattern sectors 88 are detachably connected. An arm 89 secured to the shaft 80 is normally pressed with its end bearing against the pattern sectors 88, by means of a spring 90, one end of which is attached to the bracket 91 and the other end to an arm 92, Fig. 5, secured to the shaft 80, and so long as a continuous series of sectors are presented to the arm 89, the shaft 80 and consequently the yoke 78 will not be moved to throw the clutch members 76 and 77 into operative engagement. By arranging the sectors 88 upon the disk 87 so that a vacant space 93 will be presented to the end of arm 89 upon the completion of a piece of work, the clutch members will be thrown into engagement, and the high speed be given the parts to return them to their starting position. Since the disk 87 and connected sectors rotate in

unison with the actuating means for the front and back spindles, it follows that, as soon as the cutting tools have been returned for the commencement of another cut, the 5 blank space in the line of sectors will have passed the end of the arm 89 and it will then ride over the sectors again, thereby throwing out the high speed devices. Whenever members 76 and 77 are clutched together the 10 worm is driven at the speed of the pulley 20, the rolls in disks 33 rolling to the small diameter of its slots and out of contact with gear 32. Therefore, the high speed can be used at any time and the slow speed becomes 15 operative the instant the members 76 and 77 are unclutched, and without clash or jar. In order that shaft 80 may be turned by the hand device 79, even when the arm 89 is riding on the sectors 88, a stud 94 on the hub 20 of arm 89 engages a slot in the shaft 80, and a spring 95 is interposed between and attached to the hubs of levers 79 and 89 tending to force the two arms in opposite directions. Of course, any usual and well known devices 25 may be used for this purpose. It will thus be seen that having arranged the sectors to throw in the high speed devices on the completion of a piece of work, the cutting instrumentalities will be returned to their position for another cut automatically, or, if desired at any time, this can be done by hand.

In finishing certain articles it is desirable that an end cut be given and means are 30 herein provided for simultaneously effecting this as the front and back cutting devices are in operation, one form of such end cutting devices and the feed therefor being indicated in Figs. 3 and 8.

40 The counter shaft 84, driven from the worm 15 and connected parts, as hereinbefore explained, extends longitudinally of the lathe-bed and is carried in suitable bearings 96, 96, Fig. 3, and is provided with a pinion 45 97 which engages suitable teeth 98 formed in or upon a tail drum 99. The said drum 99 is mounted loosely upon the tail stock end of the front feed spindle 12 and is prevented from longitudinal movement by means of an 50 arm 100, secured to the tail stock and having a part 101 embracing the front feed spindle, as will be seen most clearly in Fig. 3. Secured to the surface of tail drum 99 are suitable cam strips 102, 102, forming between them a cam groove for a stud 103 connected to the tail carriage 104. The stud 103 is preferably, though not of necessity, adjustable longitudinally of the tail carriage by means of a screw 125, see Fig. 8, to allow of 55 finer setting after the tool-holder 105 mounted on the carriage 104 has been clamped roughly in place. The tool holder 105 may be secured to the carriage 104 in any suitable manner, as by bolts 106, and 60 more than one cutter 107 may be supported

thereby if desired; likewise, this form of tool holder may provide a support 108, Fig. 8, for the turning arbor. Thus it will be noted that the entire series of cutters are moved simultaneously in their cutting operations, 70 and all derive motion from the single source of power through the cam-drum and its connected parts, whereby the several cutting operations are not only carried on at one time, but each completes its cycle of 75 action at substantially the same moment and is then automatically returned under high speed for the commencement of another cut, it being understood that, in case of the tail or end cutting devices, this is accomplished 80 by suitable returning cams secured to the tail drum if the character of the end cut requires it.

A cycle of operations having been performed as explained and the parts returned 85 to their starting position it becomes desirable to stop the machine to introduce a new blank. Mounted in suitable bearings connected to the lathe-bed and the floor beneath is a stop rod 109 carrying a stop arm 110, the end of 90 which travels in the groove 111 formed in the disk 87, a spring 112 normally tending to turn the stop rod 109 to hold the end of the arm 110 in said groove. Adjustably secured in the groove 111 is a stop pin 113, 95 which is adapted to lift the arm 110, when, by the rotation of the disk, it is brought into engagement with the end of said arm. Secured to the stop rod 109 near its lower end is a catch arm 114, Fig. 6, having a latch or 100 catch 115 adapted to engage a foot lever 116 and hold the same in depressed position so long as the end of stop arm 110 travels in the groove 111, but should the stop arm be met by the stop pin 113, it will be pushed out- 105 ward against the tension of spring 112, thereby turning the stop rod 109 and the catch arm 114 secured to it and freeing the foot lever 116 to the raising action of a spring 117, shown in dotted lines, Fig. 6. Connected to the foot lever 116 by means of an arm 118 is an upright rod 119 leading to any usual form of power disconnecting means, not necessary to illustrate, as it forms no part of the present invention and is, moreover, well known to those skilled in the art, 110 whereby, upon the upward movement of said rod 119 the driving power is operatively disconnected from the machine. A hand lever 120 is connected to the stop rod 109 whereby 115 it may be turned by hand and the machine stopped when desired. When a new blank has been put in the machine, it is only necessary to depress the foot lever 116, thus throwing in the operative power. The 120 various stopping, starting and speed controlling means are preferably arranged in close proximity to each other so that the operative may not have to move from an advantageous position for work inspection 125 130

6
to manually control the entire operation of the machine.

In the form of machine hereinbefore described, particular attention has been given

- 5 the construction adapted to finish a pulley by facing it, beveling its edges and end cutting it, so that the article comes from the machine in completed condition or substantially so after one cycle of the machine operation; but
- 10 it is to be understood that the invention is applicable to a large variety of work, in fact, one or more of the cutting or other mechanism may be rendered inactive in working upon some varieties of articles, or changes
- 15 may be made in the details of parts or their arrangements and relation within the province of the present invention, which is more definitely pointed out in appropriate scope by the claims hereunto attached.

20 Having thus described my invention, what I claim and desire to secure by Letters Patent is:

- 1. In a lathe, a cam-drum having cam surfaces on its interior and exterior surfaces, 25 means for revolving said drum, a plurality of feed spindles, tool holders connected to said spindles, and operative connections between the cam surfaces of said drum and said spindles for causing the tool holders to be simultaneously operated.

2. In a lathe, a feed spindle carrying a tool holder, a cam-drum concentrically arranged with respect to said feed spindle, cam plates secured to the inner surface of said cam-drum, an arm or dog connected to the feed spindle and engaging the cam plates on said drum and means for revolving said drum.

3. In a lathe, a cam-drum, means for rotating said drum, a back feed spindle, a tool holder carried thereby, connections between the drum and spindle for moving the latter longitudinally, and means for moving the spindle about its axis as it is moved longitudinally.

4. In a lathe, a cam-drum, means for rotating said drum, a back feed spindle, a tool holder carried thereby, connections between the drum and spindle for moving the latter longitudinally, a controlling arm secured to said spindle, and a cam plate for acting upon said controlling arm to turn the spindle about its axis as it is moved longitudinally.

5. In a lathe, a cam drum, means for rotating said drum, a back feed spindle, a tool holder carried thereby, connections between the spindle and cam drum for moving the former longitudinally, a cam plate, means for angularly adjusting said cam plate, a controlling arm secured to the back feed spindle and 60 connections between the controlling arm and cam plate for turning the spindle as it is moved longitudinally.

6. In a lathe, a longitudinally movable back feed spindle, a controlling arm secured 65 thereto, a cam plate having a groove in

which the end of said arm travels, a cam, means for rotating it, and connections between the spindle and cam for oscillating the former from the latter.

7. In a lathe, a longitudinally movable 70 back feed spindle, a controlling arm secured thereto, a cam plate having a groove in which the end of said arm travels, means for adjusting the cam plate to vary the angular relation between the groove and the axis of 75 the feed spindle, a cam, means for rotating it, and connections between the spindle and cam for oscillating the former from the latter.

8. In a lathe, the combination of a back-feed spindle, a cam drum adapted to move 80 said spindle longitudinally, a cam rotatable in a plane at right angles to said spindle adapted to oscillate the same, a controlling arm secured to the back-feed spindle, an angularly - adjustable cam - plate engaged by 85 said arm, a releasable dog or arm, and a releasable cam - arm for engaging the cam-drum and cam respectively according to the angle of adjustment of the cam-plate.

9. In a lathe, a driving shaft, a cam drum 90 or cylinder driven from said shaft, an outwardly projecting bearing secured to said drum or cylinder, cams carried by said drum or cylinder, a feed spindle passing centrally through said drum or cylinder and movable 95 longitudinally thereof through said outwardly extended bearing, and operating connections between said spindle and the cams on said drum or cylinder.

10. In a lathe, the combination of a front 100 feed spindle and backfeed spindle, a single cam drum for simultaneously operating said spindles, an end feed carriage, a cam drum for moving said carriage longitudinally of the lathe bed, a single driving shaft and suitable 105 connections between said driving shaft and the aforesaid drums, whereby the latter are simultaneously driven by the former through a complete cycle of cutting operations.

11. In a lathe, a feed spindle, a tool-carriage mounted thereon and movable therewith, a cam-drum, connections between said drum and said spindle for moving the latter longitudinally of the lathe-bed, and a former plate directly engaging the aforesaid tool-carriage.

12. In a lathe, a front-feed spindle, a tool-carriage thereon and movable therewith; a cam drum, connections between said drum and said spindle for moving the latter longitudinally of the lathe-bed, and a movable former-plate directly engaging the aforesaid tool-carriage.

13. In a lathe, a front-feed spindle, a tool-carriage mounted thereon and movable 125 therewith, a cam-drum, connections between said drum and said spindle for moving the latter longitudinally of the lathe - bed, a former-plate, connections between the said plate and the aforesaid drum, whereby said 130

plate is moved longitudinally of the lathe bed and connections between said plate and the aforesaid tool-carriage, whereby said tool-carriage is oscillated during its longitudinal movement.

14. In a lathe, a front feed spindle, a back feed spindle, a cam drum provided with means for imparting a longitudinal movement to both spindles, and means for oscillating both spindles during such longitudinal movement.

15. In a lathe, a back feed spindle, a cam drum, connections between said drum and spindle for moving said spindle longitudinally of the lathe bed, a cam plate and a cam independent of said cam-plate, separate connections between said cam plate and said independent cam respectively and the aforesaid back-feed spindle.

20 16. In a lathe, a back feed spindle, a cam plate adapted to be held stationary, connections between said cam plate and said spindle for moving said spindle longitudinally of the lathe bed, and a cam movable by the 25 operation of the lathe and connections between said cam and said spindle.

17. In a lathe, a back feed spindle, a cam drum, a cam plate, releasable connections between said plate and said spindle and releasable connections between said drum and said spindle, a rotary cam and connections between said rotary cam and said spindle for oscillating said spindle during its longitudinal movement.

35 18. In a lathe, a back feed spindle, a cam drum, detachable connections between said drum and spindle for moving the spindle longitudinally of the lathe bed, a cam plate adapted to impart either a longitudinal or an 40 oscillatory movement to said spindle, detachable connections between said spindle and said cam plate, a cam independent of said cam plate and detachable connections between said independent cam and said back feed spindle.

19. In a lathe, a spindle, a tool carriage mounted thereon, a cam drum, a drive shaft, connections between said drum and said shaft whereby the drum is driven from 50 the shaft, connections between the aforesaid spindle and said drum for moving said spindle longitudinally of the lathe bed, a former plate and connections between said former plate and the aforesaid tool carriage whereby 55 said tool carriage is oscillated during its longitudinal movement.

20. In a lathe, a spindle, a tool carriage thereon, a cam drum, a drive shaft, connections between said drum and shaft whereby 60 the drum is driven from the shaft, a former plate, releasable connections between said former plate and said spindle respectively and said drum, whereby said elements may be longitudinally movable from said drum either separately or simultaneously, and con-

nctions between said former plate and said tool carriage whereby said tool carriage is oscillated during its longitudinal movement.

21. In a lathe, a spindle, a tool carriage on said spindle, a cam drum, cam patches on both the exterior and the interior surfaces of said drum, a drive shaft, connections between said drive shaft and said drum, whereby the drum is driven from the shaft, a former plate, connections between said spindle and said former plate whereby said spindle is oscillated and connections between the interior cam patches and exterior cam patches of said cam drum and the said former plate and said spindle respectively, whereby 80 said spindle and said former plate are moved longitudinally.

22. In a lathe, a spindle, a tool carriage on said spindle, a cam drum, cam patches on both the exterior and the interior surface of 85 said drum, a drive shaft, connections between said drive shaft and said drum, whereby the drum is driven from the shaft, a former plate, connections between said spindle and said former plate whereby said spindle is oscillated and releasable connections between the interior cam patches and exterior cam patches of said cam drum and the said spindle and said former plate respectively, whereby 90 said spindle and said former plate are moved longitudinally, either separately and independently or simultaneously as desired.

23. In a lathe, a spindle, a tool carriage thereon, a cam drum, a drive shaft, connections between said drum and shaft whereby 100 the drum is driven from the shaft, a former plate, releasable connections between said former plate and said spindle respectively and said drum whereby said elements may be driven from said drum either separately 105 or simultaneously, connections between said former plate and said tool carriage whereby said tool carriage is oscillated during its longitudinal movement, and means for locking said former plate in a stationary position 110 when the same is disconnected from the aforesaid cam drum.

24. In a lathe, a spindle, a tool carriage mounted thereon and free to move vertically, means for imparting a longitudinal movement to said spindle, a resting edge supported by said carriage and free to move laterally, a former plate arranged to engage said resting edge, means for holding said resting edge temporarily at rest, and means 115 engaged by said resting edge for raising and lowering said carriage while said resting edge is temporarily at rest.

25. In a lathe, a spindle, a tool carriage mounted thereon and free to move vertically, 125 means for imparting a longitudinal movement to said spindle, a resting edge supported by said carriage and free to move laterally, a former plate arranged to engage said resting edge, and provided with shoul- 130

ders arranged to hold said resting edge temporarily at rest, and means engaged by said resting edge for raising and lowering said carriage while said resting edge is temporarily at rest.

26. In a lathe, a spindle, a tool carriage mounted thereon and free to move vertically, means for imparting a longitudinal movement to said spindle, an inclined pin supported by said carriage, a laterally movable resting edge mounted on said pin, a former plate arranged to engage said resting edge, and means for temporarily arresting the movement of said resting edge.

27. In a lathe, a spindle, an oscillating tool carriage thereon, a former plate movable beneath said carriage and adapted to oscillate the same, means for simultaneously moving both said tool-carriage and said former-plate longitudinally of the lathe-bed in the same direction at relatively different speeds and a member carried by the said carriage and adapted to be engaged by said former plate to lift the aforesaid tool-carriage onto the said former-plate.

28. In a lathe, a spindle, a tool-carriage thereon, means to move said spindle and tool-carriage longitudinally of the lathe-bed, a former-plate, a wedging element below said tool-carriage, a shoulder on the aforesaid former-plate, with which said wedging element is adapted to engage and through such engagement to be temporarily arrested while the tool-carriage continues its longitudinal movement, thereby forcing the tool-carriage over the wedging element and raising it onto the aforesaid former-plate.

29. In a lathe, a spindle, a tool-carriage thereon and movable therewith, means to move said spindle and carriage longitudinally of the lathe-bed, a former-plate, an inclined pin mounted in the under face of the aforesaid carriage, a wedging element movably mounted on said pin, a shoulder on the aforesaid former plate, by which said wedging element is adapted to be temporarily arrested during the continued longitudinal movement of said tool-carriage.

30. In a lathe, a spindle, a tool-carriage on said spindle and movable therewith, means to move said spindle and tool-carriage longitudinally of the lathe-bed, a wedging element beneath said carriage, loosely mounted on an inclined pin, said inclined pin being attached to the aforesaid tool-carriage, a former-plate, and a shoulder on said former-plate adapted to engage the aforesaid wedging member and temporarily arrest the same during the longitudinal movement of the tool carriage to thereby raise said carriage onto said plate by the co-operation of said wedging element and said inclined pin.

31. In a lathe, a feed spindle, a tool-carriage on said spindle and movable therewith, a sleeve on one end of said spindle, two

cam drums one secured to said sleeve and the other concentric with the opposite end of said spindle respectively, a drive shaft, connections between said drive shaft and said drums respectively whereby said drums are driven from said shaft, an end feed carriage, connections between one of said drums and said spindle and the other of said drums and the aforesaid end feed carriage whereby said spindle and said end feed carriage are moved longitudinally.

32. In a lathe, a front feed spindle, and an end feed carriage, two cam drums, a drive shaft, connections between each of said drums and said drive shaft whereby said drums are driven from said shaft, detachable connections between said drums and said front feed spindle and said end feed carriage respectively whereby said spindle and said end feed carriage may be given either simultaneous longitudinal movement or separate longitudinal movement.

33. In a lathe, a front feed spindle, a tool carriage thereon, an end feed carriage, two cam drums, connections between said drums and said front feed spindle and said end feed carriage respectively whereby said spindle and said end feed carriage are moved longitudinally, a drive shaft, connections between one of said drums and said shaft for driving said drum, a counter shaft and connections between said counter-shaft and the other of said drums and the aforesaid drive shaft respectively whereby the last-named drum is driven by the drive shaft.

34. In a lathe, a front feed spindle, two cam drums concentric therewith, an end feed carriage, connections between one of said drums and said spindle and the other of said drums and said end feed carriage respectively for moving said spindle and said end feed carriage longitudinally, a drive shaft, connections between said drive shaft and one of said drums, a counter-shaft, connections between said counter-shaft and the other of said drums and said drive shaft respectively whereby both said drums are driven simultaneously from the same drive shaft.

35. In a lathe, a front feed spindle, a back feed spindle, tool carriages adapted to be fed thereby, and an end feed carriage, a cam drum, connections between said cam drum and said front and back feed spindle respectively whereby said spindles are moved longitudinally, a second cam drum, connections between said drum and the aforesaid end feed carriage whereby said carriage is moved longitudinally, a drive shaft and connections between said shaft and the said drums respectively whereby said drums and their connected elements are operated simultaneously and in unison.

36. In a lathe, a front feed spindle, a tool carriage thereon, a back feed spindle, a tool carriage thereon, a cam drum, detachable

connections between said drum and each of said spindles respectively, a second cam drum, an end feed carriage, detachable connections between said drum and carriage, a 5 drive shaft, and connections between said drive shaft and each of said drums respectively whereby any one of said tool carriages may be moved longitudinally independently of the remaining tool carriages or any two or 10 all of said tool carriages may be given simultaneous longitudinal movement.

37. In a lathe, a front feed spindle, a back feed spindle, a tool carriage on each of said spindles, a cam drum, connections between 15 said front feed spindle and said cam drum whereby said front feed spindle is moved longitudinally, a sleeve secured to the drum in which said front feed spindle is journaled and slideable, a cam disk on said sleeve and 20 connections between the aforesaid back feed spindle and said cam disk whereby said back feed spindle is oscillated.

38. In a lathe, a back feed spindle, a tool carriage thereon, a front feed spindle, a tool 25 carriage thereon, a cam drum, connections between said drum and said spindles respectively whereby said spindles are moved longitudinally, a sleeve secured to the drum in which said spindle is journaled and slideable, 30 a cam disk on said sleeve and connections between said disk and said back feed spindle whereby said back feed spindle is oscillated.

39. In a lathe, a back feed spindle, a tool carriage thereon, a front feed spindle, a tool 35 carriage thereon, a cam drum, connections between said drum and said spindles respectively whereby said spindles are moved longitudinally, a sleeve secured to the drum in which said spindle is journaled and slideable,

a cam disk detachably secured on said sleeve 40 and connections between said disk and said back feed spindle whereby said back feed spindle is oscillated.

40. In a lathe; a front feed spindle, a tool-carriage thereon and movable therewith, and 45 an end feed carriage, a cam drum, connections between said cam drum and said front feed spindle whereby said spindle is moved longitudinally, a sleeve freely rotatable on said spindle and secured to said cam drum, a 50 gear on said sleeve, a second cam drum, a counter-shaft and connections between said counter-shaft and said gear and said second drum respectively whereby said second drum and its connected carriage are driven. 55

41. In a lathe, a feed spindle, a cam drum, connections between said spindle and said drum whereby the latter may be moved longitudinally from the former, a sleeve freely rotatable on said spindle and secured to the 60 cam drum, a counter-shaft, connections between said counter-shaft and said rotatable sleeve whereby said counter-shaft is driven, a pattern shaft, connections between said pattern shaft and said counter-shaft for 65 driving the former, a pattern plate, on said pattern shaft, an automatic speed-changing device and connections between said speed changing device and said pattern - plate, whereby said speed-changing device is operated at regular predetermined intervals. 70

In testimony whereof I affix my signature in presence of two witnesses.

RIMMON C. FAY.
